United States Patent Office.

GEORGE H. HAWKINS, OF NEW YORK, N. Y.

Letters Patent No. 71,751, dated December 3, 1867.

IMPROVEMENT IN PILL AND OTHER BOXES.

The Schedule referred to in these Letters Patent and making part of the same.

TO ALL WHOM IT MAY CONCERN:

Be it known that I, GEORGE H. HAWKINS, in the city, county, and State of New York, have invented a new and useful Improvement in Pill and other Boxes; and I do hereby declare that the following is a full, clear, and exact description thereof, which will enable others skilled in the art to make and use the same, reference being had to the accompanying drawings, forming part of this specification.

Figure 1 is a perspective view of my improved box.

Figure 2 is a sectional view of the same.

Similar letters of reference indicate corresponding parts.

My invention has for its object to furnish an improved box for containing pills and other things, which shall be simple in construction, more reliable in use, and manufactured at a less expense than the ordinary paper boxes now in use for such purposes; and it consists in forming the boxes of buckram, or other woven fibrous material, stiffened with starch or other glutinous matter, and stamped into shape with hot metal dies, while moist or damp.

A is the box, and B is the cover, which is made a little larger than the box A, so as to easily fit upon it. The box and cover are cut out of buckram, or other woven fibrous material, into the proper size. The said cloth, either before or after the boxes have been cut out, is stiffened with ordinary starch, or other suitable glutinous material. The pieces are then moistened or dampened, and while in this state, are struck up into proper shape by means of hot metal dies of the proper size and form. The edges of the boxes are then trimmed off, and their manufacture is completed.

I claim as new, and desire to secure by Letters Patent—

Forming pill or other boxes of buckram, or other woven fibrous material, stiffened with starch or other glutinous material, and struck up into proper shape while moist or damp, by means of hot metal dies, substantially as herein shown and described.

The above specification of my invention signed by me, this 1st day of July, 1867.

GEO. H. HAWKINS.
